(57) **CLAIM**

The ornamental design for a tubular clothes hanger, as shown and described.

DESCRIPTION

FIG. 1 is a side view of a tubular clothes hanger showing my new design;

FIG. 2 is a top view thereof;

FIG. 3 is an end view thereof; and,

FIG. 4 is side view of the tubular clothes hanger in use.

The broken lines shown in the drawing disclosure are for illustrative purposes only and form no part of the claimed design.
